FASTENING FORMING AND DELIVERING
MECHANISM

Fred C. Eastman, Marblehead, Mass., assignor to
United Shoe Machinery Corporation, Paterson,
N. J., a corporation of New Jersey

Application July 27, 1934, Serial No. 737,180

36 Claims. (Cl. 1—27)

This invention relates to fastening inserting machines and is illustrated herein as embodied in a machine constructed and arranged to form fastenings from a length of fastening material and to deliver the fastenings into the path of movement of the fastening inserting instrumentalities of the machine.

The fastening together of shoe parts by means of paper pegs, as disclosed and claimed in United States Letters Patent No. 1,729,169, granted September 24, 1929, on an application filed in the name of Fred N. LaChapelle, has proved to be commercially successful, and fastening inserting machines particularly adapted to the insertion of fastenings of this character and which form the fastenings from a length of fastening material and drive a single fastening in each cycle of operation of the machine are now being used extensively in the manufacture of shoes.

It is an object of the present invention to provide an improved gang fastening inserting machine having fastening, forming and delivering mechanism arranged to sever fastenings from a length of fastening material and to deliver the fastenings to a plurality of driver passages in a fastening receiving block or die. To this end a feature of the invention resides in a mechanism provided with means for forming fastenings from a length of fastening material, a fastening receiving member having a plurality of passages located in the path of movement of a corresponding number of fastening inserting tools, and means for delivering fastenings successively to the passages in said member. The illustrated machine is provided with a clamping block having a plurality of driver passages and a plurality of fastening receiving passages intersecting said driver passages. The fastenings are delivered to the passages in said block by a member provided with a fastening receiving passage, said member being rotated step by step to bring the fastening receiving passage in the member into alignment with successive passages in an intermediate block. The illustrated machine is provided with means arranged to move severed fastenings from a severing means to successive fastening receiving passages in the clamping block.

Another object of the invention is to provide an improved machine arranged to form and deliver fastenings and to insert a plurality of fastenings during one cycle of operation of the machine. As illustrated, the machine is provided with a block having a plurality of driver passages and fastening receiving passages opening into the driver passages, a gang of drivers, means

arranged for step-by-step rotary movement to deliver the severed fastenings to successive fastening receiving passages in the block, and spring means constructed and arranged to move the fastenings in the fastening receiving passages in said block into said driver passages prior to the fastening inserting operation.

With the above and other features and objects of the invention in view the invention will now be described with respect to the accompanying drawings which illustrate a preferred embodiment of the invention and pointed out in the claims.

In the drawings,

Fig. 1 is a view in side elevation of a machine embodying the present invention, part of the machine being shown in cross section;

Fig. 2 is a horizontal section on the line II—II of Fig. 1;

Fig. 3 is a vertical section on the line III—III of Fig. 1;

Fig. 4 is a detail plan view on an enlarged scale of the mechanism for feeding the fastening material;

Fig. 5 is a detail view of the mechanism for adjusting the feeding movement of said mechanism;

Fig. 6 is a view in front elevation of the fastening inserting instrumentalities of the machine, part of the machine being shown in section;

Fig. 7 is a detail view of the clutch tripping mechanism for the fastening severing and feeding device; and

Fig. 8 is a cam diagram showing the operating movements of the parts of the machine.

The illustrated fastening inserting machine is arranged to supply a plurality of fibre fastenings to a gang fastening inserting mechanism of the type disclosed in United States Letters Patent No. 1,707,404, granted April 2, 1929, on an application filed in the name of Fred N. LaChapelle. It is to be understood, however, that the invention is not limited to use in such machines but may, if desired, be used with other types of fastening inserting machines.

The illustrated machine is provided with a frame 10 which carries the fastening inserting instrumentalities. An auxiliary frame 12 is secured to the main frame 10, the auxiliary frame 12 carrying the fastening severing and feeding instrumentalities. The main frame 10 is provided with a shaft 14 which carries a cam 16 for operating the fastening inserting mechanism in a manner later to be described. The shaft 14 is connected to a suitable source of power and

is intermittently operated in the manner disclosed in the above-mentioned Letters Patent.

The fastening severing and feeding mechanism is operated from a separate source of power, for example, a motor 18, shown in dotted lines in Fig. 1. The motor 18 is provided with a shaft carrying a pulley 20 which is connected by a belt 22 to a pulley 24 loosely mounted on a shaft 26 journaled in bearings 28, 30 in the frame 12 of the machine. The pulley 24 is provided with a flange 32 the inner surface of which forms a friction surface which is engaged by a clutch member 34 mounted on the shaft 26. The loose pulley 20 and the clutch member comprising the flange 32 extending from the pulley are continuously rotated. It is necessary, therefore, to provide means for bringing the fastening severing and feeding mechanism into operation at the proper time during the cycle of operation of the machine. To this end mechanism is provided for moving the clutch member 34 into engagement with the inside surface of the flange 32 formed on the pulley 24. It is to be noted that the clutch member 34 is arranged to move axially relatively to the shaft 26 but is prevented from radial movement relatively to the shaft 26 by means of a pin and slot connection 36. The loose pulley 24 is arranged to rotate relatively to the shaft 26 but is prevented from moving axially thereof by collars 38, 40 secured to the shaft. When the clutch member 34 is moved toward the left, as viewed in Fig. 1, into engagement with the flange 32, the shaft 26 is rotated thereby bringing the fastening severing and feeding mechanism into operation. This is accomplished by moving a lever arm 42 pivotally mounted on a sliding member 44. The sliding member 44 is provided with a forked end into which fits one end of a lever arm 46. The lever arm 46 being secured to the forked end of the sliding member 44 by a pin 48. The other end of the lever arm 46 is rigidly secured to a vertical shaft 50 which is mounted in bearings 52, 54. The lower end of the shaft 50 is provided with a lever arm 56 which carries a cam roll 58 engaging a cam surface formed on the rear portion of the cam member 16. When the cycle of operation of the fastening inserting instrumentalities is completed, a high point 60 on the cam member 16 engages the cam roll 58 swinging the lever 56 rearwardly, thus moving the sliding member 44 rearwardly. Interposed between the lower end of the lever 42, which encircles the shaft 26, and the clutch member 34 is a spring 62 through which movement of the arm 46 of the lever 42 is transmitted to the loose clutch member. In order to insure that the clutch member 34 is moved into engagement with the flange 32 the upper end of the lever 42 is connected to a spring plunger 64. The plunger 64 is provided with an enlarged end portion 66 between which and the frame 12 is interposed a coil spring 68. Thus, when the sliding member 44 is moved toward the left, as above described, the spring 68 is compressed, thus tending to rotate the lever 42 about its fulcrum in a clockwise direction as viewed in Fig. 1. This clockwise movement of the lever 42 is transmitted to the clutch member 34 thereby insuring that the parts of the clutch will be in proper driving contact. The sliding member 44 is moved to the left a distance sufficient to permit its beveled end 70 to be moved out of a notch or recess 71 in the hub 72 of a worm gear 74.

The shaft 26 carries a spiral gear 76 which meshes with a spiral gear 78 secured to a shaft

80 mounted in vertical bearings 82, 84 in the auxiliary frame 12. The shaft 80 carries a four-tooth worm 86 which meshes with the worm gear 74. The relation of the worm 86 to the gear 74 is such that eight revolutions of the worm 86 will rotate the gear 74 one revolution. Mounted adjacent to the upper end of the shaft 80 is a spiral gear 88 held fast to the shaft 80 by a pin 90. The gear 88 meshes with a spiral gear 92 secured to a horizontal shaft 94 mounted in bearings 96, 98 in the auxiliary frame 12. The shaft 94 carries a spur gear 102 which meshes with a spur gear 104 secured to a horizontal shaft 106 mounted in suitable bearings in the auxiliary frame 12. The spur gear 104 meshes with a spur gear 108 secured to a shaft 110 mounted in bearings 112 and 114 in the machine frame 12. The shafts 106 and 110 operate the mechanism for feeding fastening material to a shearing block 116 and for operating the mechanism for moving the fastenings from shearing or severing position into the path of movement of the fastening inserting instrumentalities of the machine.

The shaft 106 is provided with a crank 117 which is connected to a piston 118 contained in a cylinder 120. At the beginning of the cycle of operation of the fastening forming and feeding mechanism the piston 118 is in the position shown in Fig. 1 and during the first portion of the cycle of operation is moved downwardly on its intake stroke. The top of the cylinder 120 is provided with an exhaust port 122 to which is connected a pipe 124 which leads to a hole in a block 126. During upward movement of the piston 118 air contained in the cylinder is compressed. At the beginning of the downward movement of the piston 118 the shearing block 116 is moved toward the left to bring a fastening receiving hole 128 in the block 116 into alignment with the path of movement of the fastening material. The hole 128 is thus moved out of alignment with a hole 127 in the block 126, thereby closing the hole 127 and preventing escape of compressed air. The surface of the auxiliary frame 12 to which the block 126 is secured is carefully ground, as is the top surface of the shearing block 116, thereby permitting intimate contact between the surfaces which act as a seal to prevent undesired escape of compressed air.

At the time that the piston 118 begins its downward movement the shear block 116 is moved toward the left under the influence of a spring 130 surrounding a sliding bar 132 secured to the block 116. The other end of the sliding bar 132 is provided with a block 134 which carries a cam roll 136. As shown in Fig. 1, undesired movement of the block 116 toward the left is prevented by engagement of the cam roll 136 with a cam surface 138 formed on a cam member 140. The cam member 140 is secured to the shaft 106 and rotates therewith. As viewed in Fig. 3, when the shaft 106 rotates in a counterclockwise direction, rotation of the shaft will permit the spring 130 to move the sliding bar 132 toward the left until the low part of the cam is reached. In the illustrated machine the return movement, that is, movement toward the left, as viewed in Fig. 1, takes place during the first fifty degrees of rotation of the shaft 106. During the next 180° of rotation the sliding bar 132 remains in its displaced position and then moves toward the right to feed a fastening into alignment with the hole 127 in the block 126. When the fastening is brought into alignment with the hole 127 in the block 126 the piston 118 in the cylinder 120 has

nearly completed its compression stroke. The fastening is blown through the hole 128 in the block 116 and into a hole 142 formed at the center of an indexing mechanism 144 and then conveyed through tubes to a fastening inserting mechanism 246 as will later be described.

There is secured to the end of the shaft 106 a disk-like block 148 which is provided with a radial groove 150 (Figs. 4 and 5). This groove is T-shaped to receive a substantially T-shaped block 152. The ends of the slot 150 are closed by members 154, 156 which are provided with holes through which pass the non-threaded ends of a screw 158. The members 154 and 156 are held in position in the slot or groove 150 by pins 160, as shown in Fig. 5. The block 152 is provided with a threaded hole to receive the screw 158. Thus, by turning the screw 158 the position of the block 152 in the slot 150 may be varied to provide for increased or decreased length of feeding movement. When the block 152 is in the proper position it may be locked in that position by means of a set screw 162 which bears against the side of the block 152 and firmly locks it in position. Secured to the block 152 is a crank pin 164 which is provided with an enlarged end portion 166 which fits into a horizontal slot 168 formed in a sliding block 170 (Figs. 1 and 4). The block 170 is provided with a pair of vertical grooves which receive ways 171, 173 which are formed as a part of the auxiliary frame 12.

The block 170 is provided with a hole through which passes a tube 172 locked in position by a set screw 174. The hole in the tube 172 receives fastening material 176 in the form of paper twine. The paper twine is in the form of a coil which may be supported in any suitable manner. Secured to the lower end of the tube 172 is a feed dog 178 which is arranged to grip the fibre twine 176 when the dog is moved downwardly but is arranged to release the twine when the dog is moved upwardly. In order to prevent undesired reverse movement of the paper twine 176 there is provided a dog 180 which is constructed and arranged to permit the paper twine to move downwardly but which grips the paper twine to prevent undesired upward movement of the twine. The feed dog 180 is mounted on a tube 181 and is secured to the block 126 by means of a set screw 182 and is provided with a hole through which the paper twine or fastening material passes. The construction and operation of the feed dog 178 and the dog 180 is described in detail in United States Letters Patent No. 1,802,900, granted April 28, 1931 on an application filed in the names of Fred N. LaChapelle and Fred C. Eastman, to which reference may be had for a more complete disclosure of these parts. The feeding mechanism above described begins its feeding movement at the time that the shearing block 116 is returned to its extreme position toward the left as viewed in Fig. 1. The hole 128 in the block 116 is then in alignment with the tube 181. The feeding movement of the fastening material 176 continues for substantially 180° of the rotation of the shaft 106. When the feeding movement of the fastening material is completed the slide 116 is moved toward the right by the cam 140, thus shearing a fastening from the fastening material and transferring the severed fastening into alignment with the hole 127 formed in the block 126. As previously stated, the severed fastening is blown downwardly to the indexing mechanism 144 by compressed air.

The indexing mechanism 144 (Figs. 1 and 2) is arranged to rotate a tube 184 mounted on a rotat-

ing carrier 186 to feed severed fastenings into tubes leading to the fastening inserting mechanism 246. As illustrated, the indexing mechanism is arranged to rotate one-eighth of one revolution each time that a fastening is severed and fed into alignment with the hole 127 in the block 126. Referring first to Fig. 2 it is to be noted that a cam 188 is mounted on the shaft 110. The cam surface 190 on the cam 188 engages a cam roll 192 mounted on a slide 194. The slide 194 is mounted in suitable bearings 196, 198 in the auxiliary frame 12. The slide 194 is provided with a pawl 202 which engages teeth 204 on the indexing member 144. The pawl 202 is normally held between the teeth 204 by means of a spring 206 which is interposed between a collar 208 on the pawl and an extension 210 formed as a part of the slide 194, the pawl being mounted in bearings formed in the slide 194 and the extension 210. The slide is urged toward the left and the cam roll 192 is held in engagement with the cam surface 190 by means of a heavy spring 212 which surrounds the left-hand end of the slide 194, one end of the spring bearing against the machine frame 12 and the other end of the spring bearing against a nut 214 threaded on the end of the slide 194. When the slide is moved toward the right under the influence of the cam 190 the pawl 202 engages between the teeth 204 of the indexing mechanism 144 and rotates the indexing mechanism one-eighth of one revolution. Upon further rotation of the cam 188 the slide 194 is moved toward the left under the influence of the spring 212 and the pawl 202 is permitted to yield in a direction away from the indexing member to permit the pawl to pass over the top of the next succeeding tooth 204. In order to prevent reverse movement of the indexing member 144 there is provided a stop pawl 216 similar in construction to the pawl 202 which is yieldingly held against the indexing member by a spring 218 engaged at one end by a collar 220 on the pawl 216 and at its other end by a bracket 222 secured to the auxiliary frame 12. The indexing mechanism is brought into operation after the fastening severing and feeding mechanism has completed one-fourth of its cycle of operation. That is to say, the indexing operation takes place after feeding movement of the fastening material or paper twine has begun and the indexing operation is completed before the piston 118 has begun its upward movement and before the fastening feeding operation has been completed. In other words, the indexing operation is completed before a fastening has been severed from the fastening material and before the slide is moved into position to feed another fastening to the indexing means.

The rotating carrier 186 is provided with a sleeve 230 (Fig. 1), fitting into a bearing formed in the auxiliary frame 12 and a lower sleeve 232 fitting into a plate 234 mounted in a bracket 236 secured to the auxiliary frame 12. The plate 234 is provided with a plurality of threaded holes 238 which are arranged to receive threaded couplings 240. As illustrated the plate 234 is provided with eight holes but it is apparent that a different number of holes could be provided if desired, the change in the number of holes, however, being accompanied by suitable changes in the indexing mechanism 144. The couplings 240 are connected to fastening guiding tubes 242 which lead to a nailing block 244 through which the fastening inserting instrumentalities of the machine operate. The tubes 242 are flexible and bent, as shown in Fig. 1, to permit movement of the

block 244 to take place without breaking the tubes. Although the operation of the fastening severing and feeding mechanism has been described in detail it will be well to summarize briefly at this point the operation of this mechanism as a whole. The timing of the parts is clearly shown in Fig. 8 of the drawings. The timing of the piston 118 is shown by the line P. The piston moves downwardly on its intake stroke during the first 180° of the cycle of operation and moves upwardly on its compression stroke during the last 180°. The timing of the fastening feeding dog 178 is indicated by the line F. During the first 50° of the cycle of operation the fastening feeding dog 178 is being returned to its initial position and during the next 180° operates to feed the material to the fastening severing and transferring bar 116. The feeding dog then begins its return movement. The operation of the fastening severing and transferring bar 116 is indicated by the line T. During the first 50° of the cycle of operation it is moved to the left by the spring 130 to bring the hole 128 in the bar into alignment with the hole formed in the tube 181. The bar 116 then remains stationary during the next 180° of the cycle to receive the fastening material and is then moved to sever a fastening and to transfer the fastening into alignment with the hole 142 in the rotary member 144. The timing of the indexing mechanism 144 is shown by the line I. The indexing mechanism 144 remains stationary during the first 90° of the cycle of operation and during the next 90° is rotated to bring the fastening receiving hole in the tube 184 into alignment with a hole formed in the intermediate block 234.

The fastening severing and feeding operations, together with the indexing and transferring operations take place in the illustrated machine eight times before the fastenings are driven. As previously stated, the worm gear 74 makes one revolution while the shaft carrying the worm 86 makes eight revolutions. Since the other parts of the mechanism are connected by gearing having a ratio of one, complete revolution of the worm gear 74 will not take place until these eight fastening severing and feeding operations have been completed. When these operations have been completed and the gear 74 has made one revolution the beveled end 19 of the sliding member 44 will drop into the notch 71 formed in the hub 72 of the gear 74, thus permitting the clutch member 34 to be moved toward the right, as viewed in Fig. 1, out of engagement with the continuously rotating pulley 24, thus permitting the machine to be brought to a stop with eight fastenings in the block 244 in a position ready to be inserted into a work piece.

The fastening inserting mechanism, as above stated, is of the type disclosed in Letters Patent No. 1,707,404, above referred to. The machine is provided with a gang of drivers 246 arranged simultaneously to insert paper pegs to attach a rand 248 to a heel element 250. The machine is provided with a slide (not shown) which carries a work table 254 on which is placed the heel and rand which are to be pegged together. The slide and work table are moved from loading position to a position below the block 244 in the manner described in said Letters Patent. The block 244 is mounted for movement toward and from the work table 254 to apply clamping pressure to the work. Movement of the block 244 is effected through connections to a cam track 256 formed in the cam member 16. After a work

piece has been placed on the table 254 and the treadle is depressed to place the fastening inserting instrumentalities in operation, the table 254 moves into operating position below the block 244 which is then moved downwardly to clamp 5 the work. The parts of the machine are now in position to form fastening receiving holes in the work and to insert fastenings in these holes.

The cam member 16 is provided with a cam track 262 into which fits a cam roll secured to one arm of a bell crank lever 264 fulcrumed at 266 in the machine frame 10. The other arm of the bell crank lever 264 is provided with a toothed segment 268 which meshes with teeth formed on a driver bar 270. The driver bar 270 is mounted for reciprocation in ways formed in the front of the machine and is provided with an enlarged bottom portion 272 in which are mounted the fastening inserting tools 246. Referring now to Fig. 6, it will be noted that the block 244 is provided with a plurality of passages 274 which receive the fastening inserting tools 246. The block 244 is also provided with a corresponding number of passages 276 which are enlarged at their upper ends to receive the fastening guiding tubes 242. The passages 276 intersect the passages 274 at a point below the median portion of the block 244. Springs 280 form one side of the lower portion of each passage 276 and are arranged, when the fastening inserting tools 246 are moved upwardly just prior to the fastening inserting stroke, to move the fastenings into the path of movement of the fastening inserting tools 246.

The driver bar 270 is arranged for movement 35 first to form a fastening receiving hole in a work piece and then to insert fastenings in these holes. The cam track 262 is so arranged that the upper limit of the hole forming stroke indicated at A in Fig. 6 is so located that the lower end of the tools 246 does not extend above the lower ends of the fastenings in the passages 276. The tools are moved downwardly to the full line position shown in Fig. 6 to penetrate the work to form fastening receiving holes therein. The driver bar 45 is then moved upwardly to the position indicated at B in Fig. 6 which permits the lower end of the tools 246 to be moved to a point above the upper ends of the fastenings in the driver passages 276, thus permitting the springs 280 to move the fastenings into the line of drive of the tools 246. The driver bar is then moved downwardly by the cam to a position indicated at C in Fig. 6 to drive the fastenings into the work.

Although the illustrated fastening inserting 55 mechanism may advantageously be used in connection with the fastening forming and delivering mechanism of the present invention it is to be understood that other types of fastening inserting mechanism could be used if desired. For 60 example, the fastening inserting mechanism disclosed in United States Letters Patent No. 2,034,752, granted March 24, 1936, upon an application filed in my name may be used.

Having thus described my invention, what I 65 claim as new and desire to secure by Letters Patent of the United States is:

1. In a fastening forming and delivering mechanism, a clamping block provided with a plurality of fastening receiving passages, a member arranged for intermittent rotation to deliver successive fastenings to the passages in said block, means for severing the fastenings from a length of fastening material and for transferring the severed fastenings to the delivering means, and 70 75

- means connected to said delivering means for compressing a fluid to cause movement of the fastenings from the fastening severing and transferring means to successive passages in said 5 block.
2. A fastening forming and delivering mechanism having, in combination, a clamping block provided with a plurality of fastening receiving passages, a member provided with a passage 10 and arranged to rotate step by step to deliver successive fastenings to the passages in said block, means for severing fastenings from a length of fastening material and for transferring the severed fastenings to the delivering member, and means 15 constructed and arranged to cause movement of the fastenings from the fastening severing and transferring means to successive passages in said block.
3. A fastening forming and delivering mechanism having, in combination, a block provided 20 with a plurality of fastening receiving passages, means for delivering fastenings to the passages in said block, means for intermittently rotating said fastening delivering means, means for severing the fastenings from a length of fastening material and for transferring the severed fastenings to the delivering means, and means 25 constructed and arranged to move the fastenings to successive passages in the block.
4. A fastening forming and delivering mechanism having, in combination, a block provided 30 with a plurality of fastening receiving passages, an intermediate block provided with a plurality of passages, means connecting the passages in said intermediate block to the passages in said first-mentioned block, a member having a fastening receiving passage arranged to be brought into alignment with successive passages in said intermediate block, means for moving said member 35 into alignment with successive passages in said intermediate block whereby successive fastenings may be moved into passages in the first-mentioned block, and means for severing the fastenings from a length of fastening material and 40 for transferring the fastenings to said member.
5. A fastening forming and delivering mechanism having, in combination, a clamping block provided with a plurality of fastening receiving passages, a stationary block having a plurality of 45 passages, tubes connecting the passages in said stationary block to the passages in the clamping block, a rotatable member having a fastening receiving passage constructed and arranged to be brought into alignment with successive passages in the stationary block, indexing mechanism arranged to rotate said member to permit the fastenings to be delivered to successive passages in the clamping block, and means for severing fastenings from a length of fastening material and 55 for transferring the fastenings to the rotatable member.
6. A fastening forming and delivering mechanism having, in combination, a clamping block provided with a plurality of fastening receiving 60 passages, a stationary block provided with a plurality of passages, tubes connecting the passages in the stationary block to the passages in the clamping block, a rotatable member having a fastening receiving passage constructed and arranged to be brought into alignment with successive passages in the stationary block, a pawl and ratchet mechanism constructed and arranged to rotate said member to permit fastenings to be delivered to successive passages in said 65 clamping block, and means for severing fastenings from a length of fastening material and for transferring the severed fastenings to the rotatable member.
7. In a fastening forming machine means for forming fastenings from a length of fastening material, a block provided with a plurality of fastening receiving passages, and pneumatic means arranged to deliver fastenings from said forming means to successive passages in said block.
8. In a fastening forming machine a block having a plurality of fastening receiving passages, a member arranged for movement to bring a fastening receiving passage in said member into alignment with successive fastening receiving 10 passages in said block, means for forming fastenings from a length of fastening material and for moving the fastenings into alignment with the passage in said member, and pneumatic means constructed and arranged to move the fastenings from said means to successive fastening receiving 15 passage in said block.
9. A fastening forming and delivering mechanism having, in combination, a clamping block provided with a plurality of fastening receiving 20 passages, a member arranged for intermittent rotation to deliver successive fastenings to the passages in the clamping block, and means for severing the fastenings from a length of fastening material and for transferring the severed fastenings to the delivering member, and means 25 connected to the delivering member and arranged to deliver compressed air to move the fastenings from the delivering member to successive passages in the clamping block.
10. A fastening forming and delivering mechanism having, in combination, a clamping block provided with a plurality of fastening receiving 30 passages, a member arranged for intermittent rotation to deliver successive fastenings to the passages in said block, means for severing the fastenings from a length of fastening material and for transferring the severed fastenings to the delivering member, and a reciprocating pump arranged to deliver compressed air to said member 35 to move the fastenings to successive passages in the clamping block.
11. A fastening forming and delivering mechanism having, in combination, a clamping block provided with a plurality of fastening receiving 40 passages, a member provided with a passage and arranged to rotate step by step to deliver successive fastenings to the passages in said block, means for severing the fastenings from a length of fastening material and for transferring the severed fastenings to the delivering member, and a pump connected to said delivering member arranged to deliver compressed air to move the fastenings from the delivering member to successive 45 passages in the clamping block.
12. A fastening forming and delivering mechanism having, in combination, a block provided with a plurality of fastening receiving passages, an intermediate block having a plurality of fastening receiving 50 passages, means connecting the passages in the intermediate block to the passages in the clamping block, a member having a fastening receiving passage arranged to be brought into alignment with successive passages in the intermediate block, means for moving said member 55 to align the passage in said member with successive passages in the intermediate block whereby successive fastenings may be delivered to successive passages in the clamping block, means for severing the fastenings from a length of fastening material and for transferring the severed fastenings to the delivering member.

material and for transferring the severed fastenings to the fastening receiving passage in said last-mentioned member, and a pump connected to said member and arranged to deliver compressed air to move fastenings from the fastening severing and transferring means to successive passages in the clamping block.

13. A fastening forming and delivering mechanism having, in combination, a clamping block provided with a plurality of fastening receiving passages, a stationary block provided with a plurality of passages, tubes connecting the passages in the stationary block to the passages in the clamping block, a rotatable member having a fastening receiving passage constructed and arranged to be brought into alinement with successive passages in the stationary block, an indexing mechanism arranged to rotate said member to permit fastenings to be delivered to successive passages in the stationary block, means for severing fastenings from a length of fastening material and for transferring the severed fastenings to the fastening receiving passage in the rotatable member, and a pump connected to said rotatable member and arranged to deliver compressed air to move the fastenings from the rotatable member to successive passages in the clamping block.

14. A fastening forming and delivering mechanism having, in combination, a block arranged for movement toward a work piece to clamp the work piece in operating position, said block being provided with a plurality of fastening receiving passages, means for delivering fastenings successively to said passages in said block, a member for severing fastenings from a length of fastening material and for transferring the severed fastenings to the delivering means, and means for rotating said delivering means between successive fastening severing and transferring operations.

40 15. A fastening forming and delivering mechanism having, in combination, a block arranged for movement toward a work piece to clamp the work piece in operating position, said block being provided with a plurality of fastening receiving passages, an intermediate block provided with a plurality of passages, tubes connecting the passages in the intermediate block to the passages in the clamping block, a rotatable member having a fastening receiving passage constructed and arranged to be brought into alinement with successive passages in the stationary block, indexing mechanism arranged to rotate the rotatable member to permit the fastenings to be delivered to successive passages in the clamping block, and means for severing fastenings from a length of fastening material and for transferring the severed fastenings to the rotatable member.

16. A fastening forming and delivering mechanism having, in combination, means for severing fastenings from a length of fastening material, a fastening receiving block, a member arranged to deliver the severed fastenings successively to the fastening receiving block, and means for transferring the fastenings from said severing means to the fastening receiving block, said means including a compressor having a port arranged to be connected to the delivering mechanism and arranged to discharge air after a fastening has been severed to move the fastening to the fastening receiving block.

70 17. A fastening forming and delivering mechanism having, in combination, a block arranged for movement toward a work piece to clamp the work piece in operating position, said block being provided with a plurality of fastening receiving

passages, a rotatable member having a fastening receiving passage constructed and arranged to deliver fastenings to successive passages in said block, an indexing mechanism arranged to rotate said member to permit fastenings to be delivered to successive passages in the block, and means for severing fastenings from a length of fastening material and for transferring the severed fastenings to the rotatable member.

18. A fastening forming and delivering mechanism having, in combination, means for severing fastenings from a length of fastening material, a block having a plurality of fastening receiving passages, a member arranged to deliver fastenings to successive passages in said block after the fastenings have been severed from the length of fastening material, means for feeding the fastening material to said severing means, and means constructed and arranged to compress a fluid to move the fastenings into passages in said block.

19. A fastening forming and delivering mechanism having, in combination, a block provided with a plurality of fastening receiving holes and a plurality of driver passages intersecting said fastening receiving passages, means for severing fastenings from a length of fastening material, a rotatable member constructed and arranged for intermittent movement to deliver fastenings to successive fastening receiving passages in said block, means for rotating said rotatable member step-by-step after fastenings have been severed, and means constructed and arranged to compress a fluid and to release pressure on said fluid when a severed fastening has been brought into position to be delivered to the rotatable member to move the fastening to the fastening receiving passage in said block.

20. A fastening forming and delivering mechanism having, in combination, a block provided with a plurality of driver passages and a plurality of fastening receiving passages, means associated with each of said fastening receiving passages constructed and arranged to maintain the fastenings in said fastening receiving passages prior to a fastening inserting operation, an intermediate block provided with a plurality of passages, tubes connecting the passages in said intermediate block to the fastening receiving passages in said first-mentioned block, a rotatable member having a fastening receiving passage constructed and arranged to be brought into alinement with the passages in said intermediate block, means for severing fastenings from a length of fastening material and for transferring the fastenings into alinement with the passage in said rotatable member, means constructed and arranged to deliver compressed air to the severed fastenings to move said fastenings after they have been brought into alinement with the fastening receiving passage in the rotatable member, and means arranged to rotate said member between successive fastening delivering operations to bring the fastening receiving passage in said member into alinement with successive passages in said intermediate block.

65 21. A fastening forming and delivering mechanism having, in combination, a clamping block provided with a plurality of driver passages and a plurality of fastening receiving passages intersecting said driver passages, an intermediate block provided with a plurality of passages, tubes connecting the passages in said intermediate block to the fastening receiving passages in the clamping block, a member rotatably mounted on said intermediate block, said member being pro-

vided with a fastening receiving passage, means for severing a fastening from a length of fastening material, means for feeding the fastening material to said severing means, means for rotating said member step by step to bring the fastening receiving passage in said member into alignment with successive passages in said intermediate block, cam-operated means for moving said severing means to sever fastenings and to transfer the fastenings into alignment with the fastening receiving passage in said member, and means constructed and arranged to move the severed fastenings from the fastening severing means to successive fastening receiving passages in said clamping block.

22. A machine for inserting fastenings having, in combination, a work clamping block provided with a plurality of driver passages and a plurality of fastening receiving passages intersecting said driver passages, a gang of drivers for inserting fastenings in a work piece, means for reciprocating said drivers through said driver passages, means for severing fastenings from a length of fastening material, a rotatable member arranged to deliver fastenings to successive fastening receiving passages in said block, and means constructed and arranged to move said fastenings from said fastening receiving passages to said driver passages prior to the fastening inserting operation.

23. A machine for inserting fastenings having, in combination, a reciprocating member, a plurality of fastening inserting tools secured to said member, a block provided with a plurality of passages arranged to receive said tools, said block also being provided with a plurality of fastening receiving passages intersecting said tool receiving passages, means for reciprocating said tools to form fastening receiving holes in a work piece and to insert fastenings in said holes, means for delivering fastenings to said fastening receiving passages, and means constructed and arranged to move the fastenings into alignment with said tools prior to the fastening inserting operation of said tools.

24. A machine for inserting fastenings having, in combination, a reciprocating member, a plurality of fastening inserting tools secured to said member, a block provided with a plurality of passages arranged to receive said tools, said block also being provided with a plurality of fastening receiving passages intersecting said tool receiving passages, means for reciprocating said tools to form fastening receiving holes in a work piece and to insert fastenings in said holes, means for delivering fastenings to said fastening receiving passages, and spring means constructed and arranged to move said fastenings from said fastening receiving passages to said tool passages prior to the fastening inserting operation.

25. A machine for inserting fastenings having, in combination, a reciprocating member, a plurality of fastening inserting tools secured to said member, a block provided with a plurality of passages arranged to receive said tools, said block also being provided with a plurality of fastening receiving passages intersecting said tool receiving passages, means for reciprocating said tools to form fastening receiving holes in a work piece and to insert fastenings in said holes, a rotatable member for delivering fastenings to said fastening receiving passages, and spring means constructed and arranged to move said fastenings from said fastening receiving passages to said

tool passages prior to the fastening inserting operation.

26. A machine for inserting fastenings having, in combination, a reciprocating member, a plurality of fastening inserting tools secured to said member, a block provided with a plurality of passages arranged to receive said tools, said block also being provided with a plurality of fastening receiving passages intersecting said tools receiving passages, means for reciprocating said tools to form fastening receiving holes in the work piece and to insert fastenings in said holes, a rotatable member for delivering fastenings to said fastening receiving passages, and means for severing fastenings from a length of fastening material and for transferring the severed fastenings to said rotatable member, and spring means constructed and arranged to move said fastenings from said fastening receiving passages to said tool receiving passages prior to fastening inserting operation.

27. A machine for inserting fastenings having, in combination, a work clamping block provided with a plurality of driver passages and a plurality of fastening receiving passages intersecting said driver passages, a gang of drivers, means for reciprocating said drivers through said driver passages, means for severing fastenings from a length of fastening material, a rotatable member arranged to deliver fastenings to successive fastening receiving passages in said block, and spring means constructed and arranged to move said fastenings from said fastening receiving passages to said driver passages prior to the fastening inserting operation.

28. A machine for inserting fastenings having, in combination, a work clamping block provided with a plurality of driver passages and a plurality of fastening receiving passages intersecting said driver passages, a gang of drivers, means for reciprocating said drivers through said driver passages, said reciprocating means being constructed and arranged normally to maintain said drivers in position to close the fastening receiving passages but arranged prior to the fastening inserting operation to move said drivers to a position to open said fastening receiving passages to permit the fastenings to be moved into said driver passages, means for severing fastenings from a length of fastening material, a rotatable member arranged to deliver fastenings to successive fastening receiving passages in said block, and spring means constructed and arranged to move said fastenings from said fastening receiving passages to said driver passages prior to the fastening inserting operation.

29. A machine for inserting fastenings having, in combination, a plurality of drivers, a block provided with a plurality of driver passages and fastening receiving passages opening into said driver passages, means for reciprocating said drivers through said driver passages to form fastening receiving holes in a work piece and to insert fastenings in said holes, and means arranged to deliver fastenings one at a time to all of the fastening receiving passages in said block between two successive operations of the drivers in inserting fastenings in the work piece.

30. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert

fastenings in said holes, means arranged to deliver fastenings successively to the fastening receiving passages in said block, and means associated with the respective fastening receiving passages for moving the fastenings into the paths of movement of said drivers.

31. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert fastenings in said holes, said means being arranged normally to maintain the drivers in a position to close said fastening receiving passages but arranged prior to the fastening inserting operation to move the drivers to a position to open said fastening inserting passages to permit the fastenings to enter said driver passages, and means arranged to deliver fastenings to successive fastening receiving passages in said block.

32. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert fastenings in said holes, said means being arranged normally to maintain the drivers in a position to close said fastening receiving passages but arranged prior to the fastening inserting operation to move the drivers to a position to open said fastening inserting passages to permit the fastenings to enter said driver passages, and spring means associated with the respective fastening receiving passages for moving the fastenings from the fastening receiving passages into the driver passage.

40 33. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert fastenings in said holes, means for severing fastenings from a length of fastening material, means for delivering the fastenings successively to the fastening receiving passages in said block, and means arranged to move the fastenings in said block into said driver passages prior to the fastening inserting operation.

34. A machine for inserting fastenings having, in combination, a block provided with a plurality of driver passages, and fastening receiving passages opening into said driver passages, a gang of drivers, means for reciprocating said drivers through said passages to form fastening receiving holes in a work piece and to insert fastenings in said holes, said means being arranged normally to maintain said drivers in a position to close said fastening receiving passages but arranged prior to the fastening inserting operation to move said drivers to open said fastening receiving passages to permit fastenings to be moved into position below said drivers, means for severing fastenings from a length of fastening material, means for delivering the fastenings to successive fastening receiving passages in said block, and means to move the fastenings in the fastening receiving passages in said block into said driver passages prior to the fastening inserting operation. 20

35. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert fastenings in said holes, means for severing fastenings from a length of fastening material, means arranged for step-by-step rotary movement to deliver fastenings successively to the fastening receiving passages in said block, and means arranged to move the fastenings in the fastening receiving passages in said block into said driver passages prior to the fastening inserting operation. 30

36. A machine for inserting fastenings having, in combination, a block provided with a plurality of driver passages and fastening receiving passages opening into said driver passages, a gang of drivers, means for reciprocating said drivers through said driver passages to form fastening receiving holes in a work piece and to insert fastenings in said holes, means for severing fastenings from a length of fastening material, means arranged for step-by-step rotary movement to deliver fastenings successively to the fastening receiving passages in said block, and spring means arranged to move the fastenings in the fastening receiving passages in said block into said driver passages prior to the fastening inserting operation. 40

FRED C. EASTMAN.
